LIQUID PETROLEUM GAS VAPORIZER SYSTEM

William P. Freeman, Jr., Dallas, Tex., assignor to John E. Mitchell Company, Dallas, Tex., a corporation of Missouri

Application August 27, 1956, Serial No. 606,262

13 Claims. (Cl. 62—53)

The present invention relates to a vaporizer system for liquid petroleum gas and the like.

Such systems have heretofore been made, but they have presented difficulties of operation when used in cold climates because of reduction of vapor pressure and the condensing of the vaporized gas. At times it is difficult, if not impossible, to get a flow of the liquid petroleum gas to the vaporizer and of vaporized gas from the vaporizer to the point of use.

The present invention is designed to overcome these difficulties. Conventionally, the storage tank for the liquid petroleum gas is connected by a gravity-flow pipe into a vaporizer. The vaporizer maintains a liquid level in its area subjected to heat, that is automatically adjusted by the generated vapor pressure so that the amount of vaporization will balance the load requirements. The vaporizer is subjected to heat at the bottom.

The vapor outlet line has pressure regulators in it. Usually there is a first stage regulator that partially reduces the pressure, and a second stage regulator that further reduces the pressure to some value such as 11 inches of water, which is a conventional usable pressure for gas.

It has heretofore been a problem to keep the liquid flowing into the vaporizer when the air temperatures are very cold. For example, when normal butane is the L.P. gas being used, if the air temperature should get down to 32° F., there would be such a low pressure in the tank itself that the liquid is not permitted to flow to the vaporizer at all. To overcome this, the applicant has provided a pressure pump that is automatically put in operation when the pressure within the tank gets below a certain value. This has required a controlled by-pass line that permits the liquid to be driven back from the vaporizer into the storage tank despite the pump.

Additionally, the cold weather causes the vapor from the vaporizer to condense. Inevitably the piping from the vaporizer to the point of use has low spots in it. Frequently where the vaporizer is mounted outside of a house, the pipe is carried from the vaporizer down into the ground, thence along underground and finally up into the house. When the temperature is low, the vapor tends to condense in this cold, low, area of the piping. When such condensing takes place, there is the possibility of driving liquid into the household appliances designed to operate on vapor.

The applicant has overcome the second difficulty by a by-pass line that, in the preferred arrangement, extends back to the storage tank from a point adjacent but subsequent to a low area in the piping, between the two regulators, with an automatic thermostatic control that shunts the vapor flow back to the tank whenever the temperature within this by-pass or shunt line gets below a certain value.

The foregoing arrangement provides a system that will work, despite extremely cold weather and which automatically takes care of the condensing problem.

2

Other objects will appear from the description to follow.

The drawing represents a diagrammatic or schematic showing of the vaporizer system embodying the present invention.

In the drawing there is a storage tank 10 designed to be initially substantially filled with liquid petroleum gas, such as butane, propane, or mixtures of the same with possibly other hydrocarbons. This tank 10 is associated with a vaporizer 11 of the type illustrated in Jones Patent 2,526,363, the vaporizer being connected to the tank by pipe 12.

Any suitable heating means is used adjacent the bottom of the vaporizer 11 causing the liquid to vaporize and build up vapor pressure. Here an electric heating element H has been illustrated solely to typify heating means. The pressure in the top of the vaporizer causes the vapor to attempt to flow out an outlet pipe 13 in which is located a first stage regulator 14, that may be set to maintain some downstream pressure such as 30 p.s.i. If the consumption of gas is less than that generated by heating the liquid, the regulator 14 will throttle down and the pressure back of it will build up. The pressure will drive the liquid from the vaporizer 11 backwards through pipe 12 (and as will appear, through the by-pass pipe) to the storage tank, thereby reducing the amount of liquid in contact with the heated part of the vaporizer 11. Reduction of amount of liquid in contact with the heating surface of the vaporizer 11, causes reduction in the amount of liquid being vaporized, until the amount is equalized with the load requirements.

The foregoing has not been shown in detail here because it is well known to the art, including the patent referred to. The parts have not been shown in their specific relative sizes or positions, for the same reason.

Conventionally, there is a vapor line 16 that extends from the top of the storage tank 10 to the top of the vaporizer 11 so that any vapor in the storage tank may be used as needed, and as it is available, thereby saving the requirement of generating that amount. The line 16 contains some form of check-valve 17 that permits the flow from the tank to the vaporizer but not the flow in the opposite direction.

The first stage regulator 14 delivers the gas into a pipe 20. This pipe usually passes down to a low point such as the portion 21 that is underground, then has a riser 22 leading to the second stage regulator 23 and a pipe 24 that leads into the house, or other point of use. The regulator 23 maintains the vapor in the pipe 24 at low and usable pressures.

In the foregoing system, there is an electric (or other) pump 25 in the liquid supply line 12 between the storage tank and the vaporizer. This pump 25 is designed to force the liquid to the vaporizer because, under certain conditions where it is very cold, the liquid may not flow at all. There is a pressure-responsive switch 26 that controls the pump, as will appear.

A back flow pipe 27, is connected into the pipe 12, downstream from the pump 25. It is also connected through a pressure relief-valve 28 and a check-valve 29 into the top of the storage tank. The check-valve permits flow back to the tank 10 but not from the tank.

There is a by-pass pipe 30 connected into the pipe 22 downstream from the condensing section 21, but ahead of the second stage regulator 23. The pipe 30 is brought down and underground at 31, and finally rises again at 32, thence through a thermostatic control valve 34, a check-valve 36 and into the top of the storage tank 10. The thermostatic control valve 34 has a control sensing bulb 35 that causes this valve 34 to be closed except when

temperature of the sensing bulb 35 is below the predetermined value. While it is ordinarily preferable to use a thermostatic control 34 with the bulb 35, it should be recognized that pressure and temperature are interrelated functions, so that a pressure controlled valve 34 could be used, responsive to the pressure changes that correspond to the temperature changes here set forth.

Operation

In normal operation, where the surrounding temperatures are moderate, the vaporizer 11 will operate in the usual manner, without the assistance of the pump, the liquid fuel being forced from the tank 10 through the pipe 12 into the vaporizer 11, by reason of the pressure differential. The heater H, or whatever suitable heating means is provided, will tend to produce vaporization of whatever liquid is within the vaporizer 11. But since the first stage regulator 14 restricts the outflow of liquid, there may be more vapor generated than is required. As a result, the pressure in the line 13 in the top of the vaporizer will build up, and will drive the liquid backwardly into the tank 10, thereby reducing the amount of liquid exposed to the heated area of the vaporizer and reducing the amount of vapor generated, until it equals the amount to be consumed.

The vapor is driven from the first stage regulator through the pipe 20 to the second stage regulator and there reduced in pressure.

In very cold weather, the pressure within the tank 10 may go down to such a degree that it is below atmospheric pressure, and then there will be a tendency to drive the liquid back into the tank and no vaporization can occur. The electric pump overcomes this difficulty. It pumps liquid into the vaporizer. However, this creates a problem in that the vaporizer must have freedom to drive the liquid back into the tank when the pressure in the top of the vaporizer rises as aforesaid. Consequently, the back-flow line 27 is provided from the pipe 12 to the tank 10. A build-up of pressure above the liquid in the vaporizer tends to push the liquid back through the pipe 12 and into the pipe 27. When the pressure in the pipe 27 rises to a certain value, the pump will be stopped. No more liquid will be driven into the vaporizer until the excessive pressure in the vaporizer is reduced. Thereafter the pump will be automatically turned on or off, depending upon the condition at the pressure switch which, in turn, is the function of the pressure in the top of the vaporizer.

In the event that, for some reason, there remains an excessive pressure in the top of the vaporizer, even after the pump is turned off, this condition can be relieved through the relief-valve 28. If the pressure at the relief-valve rises to a point (such as 30 p.s.i.), this valve 28 will open and the liquid may be driven past the check-valve 29 and back into the storage tank.

This relief can take place, as a matter of fact, even if the pump continues to run inadvertently. Hence it not only provides the back-flow function, but also adds a safety feature to prevent excessive pressure in the vaporizer if the pump fails to shut off.

When the vapor leaves the first stage regulator and passes through the pipe 20 into the underground portion 21 it may condense in cold weather. Indeed, it may condense at any point up to the second stage regulator and drop back into the portion 21 as a liquid. This condensation may accumulate even when there is no demand for gas because the vaporizer is designed to maintain the pressure in the piping 20 corresponding to the setting of the regulator. As the gas condenses, it lowers pressure in the piping 20, which acts as an accumulator for the liquid. With such pressure reduction, more vapor is delivered to the piping to restore the pressure, and further condensation can occur. Liquid collected there might be forced into the house pipe 24 and into the gas-consuming appliances, which is danger-

ous, and it can create a false pressure in the regulator 14 and drive the liquid all out of vaporizer 11, stopping the system, even though there may be a demand for gas from the pipe 24.

To eliminate this situation, the by-pass pipe 30-31-32 is provided, this being connected into the pipe 22 ahead of the second stage regulator 23. When the ground temperature at bulb 35 goes below a predetermined value, at which condensing can take place, the valve 34 opens. This opens the whole return by-pass line. Thereupon the pressure back of the second stage regulator 23 will drive hot vapor through the pipes 28, 21, 22, 30, 31 and 32 thereby heating this piping sufficiently to avoid condensing of the vapor therein. The vaporizer is automatically operated to supply such vapor, as will be understood. Should there be any condensate in the pipe 21, the vapor pressure will force it back through the by-pass, into the storage tank, although usually it will revaporize in the by-pass.

Of course, the foregoing action cannot occur if the storage tank pressure is greater than that at the downstream side of the first stage regulator 14. If it be assumed that the regulator 14 provides a pressure of 30 or so p.s.i., in cold weather the vapor pressure of the L.P.G. will be considerably lower than that. In warm weather, the vapor pressure in the tank can exceed 30 p.s.i., so that the by-pass is ineffective. This is an advantage as it provides an automatic summer cut-out of the cold-weather by-pass.

In short, this feature is that condensation outside the building will be anticipated and automatically prevented, or if it occurs, the liquid will be driven back into the tank, when (a) the temperature at sensing bulb 35 indicates a condition cold enough for condensation to occur, and consequently opens valve 34 and (b) when the pressure on the downstream side of the first stage regulator is higher than the vapor pressure in the tank 10.

The foregoing demonstrates that the present system makes L.P.G. vaporization usable in cold climates.

What is claimed is:

1. A vaporizing system of the kind described, comprising a storage tank for vaporizable liquid, a vaporizer connected to the tank by a supply pipe that conducts vaporizable liquid to the vaporizer, an outlet pipe from the upper part of the vaporizer adapted to be connected to a vapor consuming apparatus, the outlet pipe having a condensate-trapping portion downstream of the pressure regulator hereinafter recited, a pressure regulator in the outlet pipe, to limit the vapor pressure on its downstream side to a predetermined maximum; a return by-pass pipe connected into the outlet pipe at a point spaced downstream from the regulator to receive and carry off the condensate in the outlet pipe, and leading back to the storage tank, a thermostatically controlled valve in the by-pass pipe, normally closed but thermostatically opened when the temperature adjacent the system becomes low enough to condense the vapor; whereby the vapor pressure downstream of the regulator may drive condensed vapor through the by-pass pipe back to the tank.

2. A system as in claim 1, wherein there is a second stage pressure regulator in the outlet pipe downstream of the by-pass connection, and the outlet, between the first regulator and the by-pass, has a low part constituting the entrapping portion wherein condensate may collect.

3. A system as in claim 1, wherein the vaporizer and tank are outdoors, and the outlet pipe leads from the regulator and goes underground, then up, and the by-pass is connected into the outlet pipe subsequent to the underground part.

4. A vaporizing system including a storage tank for vaporizable liquid, a supply pipe therefrom, a vaporizer connected to the supply pipe and having means to vaporize the liquid and develop pressure in the vapor; an out-

let from the vaporizer, a pressure regulator in the outlet adapted to limit the outlet pressure on its downstream side, a low area in the outlet upstream from the regulator whereat condensed vapor may collect, a by-pass pipe connected with the outlet downstream of the low area and upstream of the regulator, the by-pass pipe leading back into the tank; and a thermostatically regulated valve in the by-pass, normally closed, but opened when the temperature adjacent the system descends below a condensing value.

5. The system of claim 4, wherein the low area in the outlet is underground, and the by-pass pipe extends underground, with the thermostatic valve sensitive to ground temperatures adjacent the by-pass pipe.

6. The system of claim 4, wherein there is a first stage pressure regulator in the outlet upstream of the low area, set to maintain a pressure on its downstream side higher than the vapor pressure of the liquid at the temperature of condensing.

7. A vaporizing system for vaporizable liquid, comprising a storage tank; a vaporizer wherein the liquid may be vaporized to produce vapor under pressure, a liquid supply pipe from the tank to the vaporizer, a vapor discharge pipe from the vaporizer, means to restrict flow of vapor through the discharge pipe, the vapor discharge pipe having a condensed liquid-catching trap-like part upstream from the restricting means and below the vaporizer a by-pass return line from that part back to the tank to conduct condensed vapor therefrom and a valve in the bypass line.

8. A vaporizing system for vaporizable liquid, comprising a storage tank; a vaporizer wherein the liquid may be vaporized to produce vapor under pressure, a liquid supply pipe from the tank to the vaporizer, a vapor discharge pipe from the vaporizer, the vapor discharge pipe having a condensed liquid-catching low-level, trap-like part, and a by-pass return line from that part back to the tank to conduct condensed vapor therefrom, pump means to force liquid from the tank to the vaporizer through the supply line, and a back flow line downstream from the pump and connecting the vaporizer with the tank.

9. The system of claim 7, plus a control automatically

responsive to predetermined physical conditions of the environment of the bypass line, and a valve operated thereby, the valve being in the by-pass line to close the same when condensing conditions do not exist.

5. The system of claim 9, wherein the control is a thermostatic device responsive to temperatures adjacent parts of the system subject to condensing of the vaporized gas.

10. The system of claim 9, wherein there is a pressure-reducing device in the vapor discharge pipe downstream from the by-pass.

11. The system of claim 9, wherein there is a pressure-reducing device in the vapor discharge pipe downstream from the by-pass.

12. A vaporizing system for volatile liquids: including a storage tank, a vaporizer, a liquid-pipe from the tank to the vaporizer, a heating means to supply heat

15 to a part of the vaporizer, a vapor outlet from the vaporizer, a restricting means in the outlet, the outlet leading to a point of vapor consumption, the increase of pressure in the vaporizer driving the liquid back therefrom to reduce generation of vapor; a pump in the liquid pipe

20 to drive liquid into the vaporizer, a back flow pipe from the high pressure side of the pump and the lower part of the vaporizer back to the tank, and a relief valve in the back flow pipe, the relief valve opening when vaporizer pressure exceeds a predetermined value, to enable

25 such pressure to drive liquid from the vaporizer to reduce the rate of vaporization despite the action of the pump.

13. The combination of claim 12, together with a pressure-responsive device to stop the pump when the 30 vaporizer pressure requires exclusion of liquid from the vaporizer.
